UNITED STATES PATENT OFFICE.

JAMES H. PAIGE, OF MANCHESTER, NEW HAMPSHIRE, ASSIGNOR TO LORIN EDSON CHARLES, OF BEDFORD, NEW HAMPSHIRE.

BROOM-SUPPORT.

SPECIFICATION forming part of Letters Patent No. 605,808, dated June 14, 1898.

Application filed October 11, 1897. Serial No. 654,868. (No model.)

To all whom it may concern:

Be it known that I, JAMES H. PAIGE, a citizen of the United States, residing at Manchester, in the county of Hillsborough and State 5 of New Hampshire, have invented certain new and useful Improvements in Broom-Supports; and I do hereby declare the following to be a full, clear, and exact description of the invention, such as will enable others skilled 10 in the art to which it appertains to make and use the same.

My invention relates to improvements in supports for brooms and the like, and has for its object to simplify the construction and 15 mode of attaching the support or clasp to its base; also cheapness of manufacture.

The invention consists of a base piece or block, on the rear face of which is provided a diagonal groove for the reception of the loop 20 or head of a clasp. The clasp is preferably of one piece of metal and is first in the form of a staple, which is adapted to be inserted in suitable apertures in the groove or kerf of the base, then to be bent to its proper 25 form. The diagonal groove will permit the ends of the staple to protrude through suitable apertures made through the base and in line with the kerf to the front face of said base and be bent thereon to fasten the clasp 30 on the base without having to twist the ends of the staple to allow them to pass each other. While the groove is in a diagonal direction, it will be noted that the arms of the clasp are in a horizontal direction; and the invention 35 consists, further, in the detailed construction of the device hereinafter described and claimed.

In the accompanying drawings, forming a part of this specification, Figure 1 is a perspective view of my support. Fig. 2 is a rear view thereof. Fig. 3 is a detailed view of the clasp. Fig. 4 is a view of the blank or staple, adapted to be bent, as shown in Fig. 3, to form the clasp.

Like letters denote corresponding parts in all the figures of the drawings.

A is the base or block, and B is the clasp. The base A may be constructed of any suitable material, preferably wood, and may have 50 the usual holes or apertures, through which may be passed nails or screws for attach-

ment to a wall. In the rear face of this block I cut a diagonal groove or kerf a, and in this groove or kerf at a suitable distance apart I provide two holes a' a'. The groove is made 55 deep and wide enough to accommodate the loop or head of the clasp, so that the rear face of the base-block will be comparatively smooth or free from obstructions.

By showing the groove a running in a diagonal direction it will be noted that a staple inserted in the holes a' a' would also have its extended arms on a line transverse to the horizontal axis of the base. These arms could then be bent on a horizontal line without interference one with the other, the arms being on different planes.

By having the arms lap or cross on the face of the base, as at c, it will be readily understood that no nails or screws are necessary 70 to retain the clasp on the base.

If desired, the arms of the staple could be bent outwardly, instead of crossing each other, and would hold the clasp to the base-block.

The clasp B is composed of suitable spring metal, preferably strong spring-wire, and when completed is preferably in the form of a lyre. The clasp is first in the form of a staple the ends of which are inserted in the 80 holes a' a' in the base A, and the staple is then driven until the head or loop b rests in the diagonal groove a, thus making a smooth rear surface. The protruding arms b' b' are then bent down upon the base A and cross 85 one another, as at c. Said spring-arms b' are then curved outwardly, thence inwardly to a suitable point, and thence out to form the fingers b'', as shown, although the fingers b'' may be omitted, if desired. The clasp is thus held 90 firmly upon the base without the use of any other fastening means, and the arms b', being of strong spring metal, are so bent or curved as to bind against and hold an article inserted therein.

A broom-handle being inserted in the clasp would strike the fingers b'', and the arms b', being slightly resilient, would permit the fingers b'' to spread and guide the broom-handle into the space provided between the arms b', and after the greatest diameter of the handle had passed the fingers b'' they would spring

back into the former position, thereby retaining the handle within the clasp.

It is thought that the operation and advantages of my device will be readily understood 5 by those skilled in the art from the foregoing description.

I am aware that minor changes in the form and construction of parts herein shown and described may be made by a skilled mechanic; 10 but I desire to reserve the right to make such modifications and alterations as fairly fall within the scope of my invention.

Having thus fully described my invention, what I claim as new, and desire to secure by 15 Letters Patent, is—

1. As a new article of manufacture, a broom-support having a base-block provided with a diagonal kerf or groove, holes or apertures through the base intersecting the groove, and 20 a clasp, substantially as shown and described, provided with a loop which rests in said groove

and passes through said apertures, said loop bent to lock the clasp on the base.

2. As a new article of manufacture, a broom-support having a base-block provided with a 25 diagonal kerf or groove at the rear or back thereof, holes or apertures through the base and intersecting said groove, and a clasp, of one piece, inserted in the diagonal groove, the protruding ends or spring-arms of which are 30 bent on a parallel plane to cross each other upon the base-block forming the head or loop, said spring-arms thence bent outward, thence inward and again outward to form the holding-arms and guide-fingers, substantially as 35 shown and described.

In testimony whereof I affix my signature in presence of two witnesses.

JAMES H. PAIGE.
